SHELF ASSEMBLY

Otto Muller, Bronx, N. Y.

Application January 14, 1946, Serial No. 641,027

13 Claims. (Cl. 211—148)

1

This invention relates to shelf assemblies.

An object of this invention is to provide an improved shelf or bin assembly wherein shelving of any desired height may be provided, the shelves and supports being assembled and locked together without the use of bolts, screws or like fastening elements.

Another object of this invention is to provide in an assembly of this kind a pair of upright channel supporting members, horizontal shelf members, and locking means for locking the supporting and shelf members together.

A further object of this invention is to provide a shelf assembly wherein the parts are interchangeable, and the spacing between shelves may be varied at the will of the user.

A further object of this invention is to provide a shelf assembly wherein any one or more of the shelves may be converted into a bin of desired depth.

A further object of this invention is to provide a shelf assembly which when completely assembled will be rigid and self-sustaining.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing:

Figure 1 is a perspective view partly broken away and in section of a shelf assembly constructed according to an embodiment of this invention.

Figure 2 is a fragmentary sectional view taken on the line 2—2 of Figure 1.

Figure 3 is a perspective view partly broken away and in section of a modified assembly.

Figure 4 is a fragmentary sectional view in perspective of another modification of this invention.

Figure 5 is a fragmentary perspective view partly in section of another modified form of this invention.

Referring to the drawings, the numerals 10 and 11 designate generally a pair of opposed spaced confronting upright channel members which are of like construction and are each formed of a relatively wide body, wall or side 12 having right angle flanges 13 and 14 extending inwardly therefrom. The flange 13 has extending right angularly and forwardly therefrom a narrow flange 15 and flange 14 has extending

2

rearwardly therefrom a right angular narrow flange 16. The body or wall 12 forms opposed or confronting channels or channel members with the flanges 13—15 and 14—16 and a connection therebetween. A back wall 17 is disposed between the channel members 10 and 11 and comprises an upright plate 18, which is formed with rearwardly extending right angular flanges 19 at the opposite vertical edges thereof engageable with the forwardly extending rear flanges 15 of the channel members, so as to hold the channel members 10 and 11 against outward movement relative to each other. The channel members 10 and 11 have disposed therebetween a plurality of horizontally disposed shelf members, generally designated as 20. Each shelf member 20 comprises an elongated plate 21, which is formed at its forward longitudinal edge with an upright flange 22. The rear longitudinal edge of the plate 21 is formed with a depending right angular flange 23 and the latter flange is substantially narrower than the flange 22.

The flange 22 forms a shallow bin for retaining articles on the upper surface of the plate 21 and the flange 22 at its opposite ends is adapted to abut against the inner sides of the rearwardly extending flanges 16. The plate 21 at the opposite ends thereof is formed with a depending lug or flange 24 disposed substantially centrally of the plate 21 and a pair of oppositely or upwardly extending lugs or flanges 25 are carried by each end of the plate 21. The channel members 10 and 11 have disposed in the lower end portions thereof a base forming assembly which comprises two of the shelf members 20 disposed in vertical position with the narrow flanges 23 lowermost and extending outwardly and the wider flanges 22 uppermost and in confronting position. Flanges 24 extend outwardly and flanges 25 extend inwardly.

40 A pair of vertically disposed blocks 26 are disposed against the inner faces of flanges 25 and plates 21 between the inwardly extending flanges or lugs 25 and the adjacent ends of the flanges 22, and the blocks 26 are formed with a slot or groove 45 27 in their inner sides thereof, within which a vertically disposed spacer plate 28 is adapted to loosely engage. The upright shelf members 20 with the blocks 26 and the intermediate plate 28 form a substantially box-shaped base which engages within the channel members 10 and 11 as clearly shown in Figure 1. The lowermost of the horizontal shelf members 20 is then disposed on the upper side of the base and an elongated strip 29 formed with a plurality of spaced apart vertical slots 30 in the inner side thereof is disposed

against the inner side of the vertical flange 22. A pair of transverse shelf locking members or strips 31 longer than the width of the shelf 20 or extending beyond the edges thereof are disposed one at each end of the horizontal shelf 20, the locking member 31 engaging between the outer end of the flange 22 and the inner sides of the upright end flanges 25 and the opposite ends of the locking members 31 engage between the flanges 15 and 16 and the web or plate 12 of the channel members 10 and 11 and into the opposed channels formed by plates or sides 12 with flanges 13-15 and 14-16. When the locking members 31 are in position the channel members 10 and 11 will be locked against outward or inward movement relative to each other.

In order to provide a means whereby the superposed shelf members may be held in vertically spaced apart relation, I have provided a plurality of vertical partition members 32 which are in the form of a plate and are adapted at their lower ends to engage on the upper side of the plate 21. The forward edge of the partition 32 is engageable in a selected one of the slots 30 of the partition bar 29, and the upper end of the partition 32 bears against the lower side of the next or adjacent shelf member. The partition 32 at its upper rear corner is held against lateral movement by means of an elongated strip 33 which engages against the lower side of the plate 21 and bears against the rear flange 23. The strip 33 is formed with a plurality of notches 34 and the upper rear corner of the partition 32 is cut out, as indicated at 35, so that the partition 32 may snugly engage in a selected notch 34 and the lower edge of the strip 33 may seat on the shoulder 36 formed by the right angle cutout 35.

Referring now to Figure 3 there is disclosed a modified shelf assembly wherein a low bin is provided and in this instance the upright channel members 10a and 11a are relatively short and the rear wall 17a is also short terminating at its upper end flush with the upper ends of the channel members 10a and 11a. A pair of lower blocks 37 are disposed in the lower portions of the channel members 10a and 11a and a shelf member 20a engages on the upper edges of the blocks 37 but is shown reversed with the upstanding flange 22a at the rear and disposed against rear wall 17a and its depending flange 23a at the front. The channel members 10a and 11a shown in Figure 3 are locked together by lock members 31a and the forward elongated strip 29a which normally engages against the forward upturned flange 22 of the shelf or bottom forming member 20 when vertical partition and shelf supporting members 32 are used, is omitted in connection with shelf or bottom forming member 20a. The channel members 10a and 11a have disposed therein inner end wall members 38 which are provided at their upper edges with outwardly extending flanges 39 and at their vertical edges with vertical outwardly extending flanges 40. The lower end of the inner end wall 38 is formed with a lower outwardly extending flange 41 engaging on the upper side of a locking member 31a and at its outer edge with upstanding flanges or lugs 25. This assembly may consist of one, two, or more shelves 20a with channel members of a height to suit.

Referring to Figure 4, a front wall forming plate 43 is interposed between the strip 29c and the inner side of the vertical flange 22c, so as to provide for increased depth of the bin at the forward side thereof. The plate 43 may be of any

desired height and preferably the plate 43 is of a length to snugly engage between the inner faces of the end walls 38 in Figure 3. A price tag supporting clip 44, which is formed with a supporting hook or flange 45 engageable over the upper edge of the plate 43, is disposed on the forward edges of the shelves on the top side of the bin extension plate 43 so that the desired price tags may be positioned at any desired or selected point along the length of the plate 43. The clip 44 may be either a short clip or extend for the length of the bin.

Referring now to Figure 5, there is disclosed another modification of this invention wherein the upright channel members 10b are formed at the opposite vertical edges thereof with right angular flanges 14b and inner edges of the flanges 14b have extending right angularly therefrom flanges 16b. The flanges 16b have extending right angularly and outwardly therefrom flanges 46 as in Figures 3 and 4, which confront the web 12b of the channel member. A shelf member 20b, similar in detail to the shelf member 20, is engageable at the opposite ends thereof in the channel member 10b, being formed with upwardly extending flanges or lugs 25b and a shelf locking strip 31b is disposed between the upright flanges 14b and bears at its outer edge against the flanges 25b. The inner lengthwise edge of the locking member 31b is provided with a notch 47 within which the flange 46 is adapted to engage. The partition supporting strip 29b is adapted to engage on the upper surface of the shelf 20b and is of a length to fit between the inner edges of the locking strips 31b. In other respects the construction shown in Figures 1, 2 and 3 will be used with the construction shown in Figure 5.

With a shelf assembly as herein disclosed any desired number of shelves may be mounted between the channel members which form the vertical supports and when the shelf members are locked in position with the partitions between superposed shelf members the assembly will be rigid. If desired the shelf members 20 may be inverted so as to position the narrow flange foremost and the long wide flange 22 rearmost. Where this is done the depending flange or lug 24 will extend upwardly and the flanges 25 will extend downwardly.

If desired the shelf members 20 may be inserted so as to position the narrow flange foremost and in a downward position as seen in Figure 3 instead of an upward position, as indicated on the drawing in the other figures. This method of assembling the shelf members will provide a flat shelving without either the high or low flange extending above the front of the shelf. In this assembly no spacer bars or partitions are used; the shelving being supported and spaced vertically by shelf end spacers at each end of the shelves, similar to the construction shown in Figure 3.

The spacer bars 29 and 33 may be made the full length of the shelves. In case the shelving is permanently assembled, this is done by first setting the partitions with their lower forward ends engaged in the bar 29 and then sliding bar 33 into place. However, if it is desired to adopt the feature of changing the location of the partitions in certain shelving after it has been assembled, then the front bar 29 is made of a length that will fit between the locking bars 31 as shown on the drawings in Figures 1 and 5. This will permit bar 29 to be raised and moved forward permitting the removal of the partitions and their relocation to other positions.

The exact configuration illustrated is regarded as the optimum, but some of the desirable results inherent in this disclosure may be obtained by various slight modifications including some departure from the exact configuration shown, and it is therefore requested that the scope of the invention should be regarded as limited only by the terms of the claims.

What I claim is:

1. A shelf assembly comprising a pair of upright channel members disposed with the channels in confronting relation, vertical inturned retaining flanges on the opposite edges of said channel members, superposed shelf members between said channel members and having the ends thereof extending into the channels, vertical partitions disposed between pairs of shelf members supporting an upper shelf from a succeeding shelf, an upstanding flange at each end of a shelf, and a locking member longer than the width of said shelf engaging said retaining flanges and said upstanding flanges on the shelf for locking said shelf members and said channel members together.

2. A shelf assembly comprising opposed connected upright channel members disposed with the channels in confronting relation, vertical inturned flanges on the opposite edges of said channel members and disposed between opposed channel members, superposed shelf members between said channel members and having the ends thereof extending between opposed flanges into said channels and having upstanding lugs spaced from the inturned flanges, vertical members disposed between pairs of shelf members supporting an upper shelf member from a lower shelf member, and transverse locking members spanning said inturned flanges at the outside thereof and extending between the upstanding lugs and inturned flanges extending beyond the longitudinal edges of said shelf members at each end thereof engaging within the outer sides of said channel members between said inturned flanges and lugs for locking the shelf members to said channel members and said channel members together against outward or inward movement relatively.

3. A shelf assembly comprising a pair of upright channel members disposed with the channels in confronting relation, vertical inturned flanges on the opposite edges of said channel members, superposed shelf members between said channel members and having the ends thereof extending into said channels and provided with end lugs extending upwardly and downwardly outwardly of the inturned flanges, vertical members disposed between pairs of shelf members supporting an upper shelf from a lower shelf, certain of said lugs engaging certain of said vertical members and transverse locking members carried by the end portions of said shelf members extending beyond the longitudinal edges of said shelf members at each end thereof between other of the lugs at the ends of the shelves and engaging said inturned flanges for locking said channel members together.

4. A shelf assembly comprising opposed spaced upright channel members disposed with the channels in confronting relation, vertical inturned retaining flanges on the opposite edges of said channel members, superposed shelf members between said channel members and having the ends thereof engaging said flanges and extending outwardly beyond the same into the channels, flanges at the ends of the shelf members, a locking member longer than the width of said shelf disposed

between the flanges of the channel members and shelf members and in interlocking engagement with the flanges of the channel members, and means at the ends of the shelves for supporting the shelves in spaced relation, said means being disposed within the channels between the shelves and engaged with the inturned flanges of the channel members.

5. A shelf assembly comprising pairs of connected channel members having inturned inner flanges and disposed with their channels in confronting relation, superposed shelf members between said channel members and having the ends thereof extending within the channels between the flanges, oppositely bent flanges at the ends of the shelf members, horizontal transverse end members at the ends of the shelf members in interfitting engagement with the flanges of the shelves and upright channel members, vertical members disposed at the ends of the shelf members and supporting an upper shelf from a succeeding shelf and means for locking said shelf members and said channel members together.

6. A shelf assembly comprising spaced pairs of upright channel members having inwardly directed flanges with their inner edges directed inwardly into the channels and disposed with the channels in confronting relation, superposed horizontal and vertical shelf members between said channel members and having the ends thereof extending between the flanges into the channels and having end lugs, vertical transverse end members at the ends of the shelf members and supporting the latter in spaced relation, horizontal locking strips longer than the width of the shelf members cooperating between the lugs of the shelf members and flanges of the channel members for locking said channel and shelf members against relative inward and outward movement and means for locking said locking strips and said channel members together at said flanges.

7. A shelf assembly comprising spaced opposed upright channel members having inwardly directed right angular flanges with their inner edges directed inwardly at right angles and disposed with the channels in confronting relation, superposed shelf members between said channel members and having the ends thereof extending into the channels and their ends bent and free of direct connection to said channel members, horizontal transverse end members at the ends of the shelf members and longer than the width of the shelf members in interlocking engagement with and between the bent ends of the shelf members and flanges of the upright channel members to lock said shelf and channel members together, and vertical members at the ends of and between the shelf members and supporting an upper shelf from a succeeding shelf, said horizontal transverse end members preventing separation of the channel members, shelf members and vertical members relative to each other.

8. A shelf assembly comprising opposed spaced upright channel members having inwardly directed right angular flanges with their inner edges directed inwardly and outwardly into the channels and disposed with the channels in confronting relation, superposed shelf members between said channel members and having the ends thereof extending into the channels and provided with end flanges and upturned and downturned flanges at their opposite longitudinal edges, horizontal transverse end members at the ends of the shelf members and longer than the

width of the shelf members in interlocking engagement with and between the end flanges of the shelf members and upright channel members, said horizontal transverse end members having notches receiving the flanges of the channel members therein at their inner edges within the channels, vertical members between the shelf members, and longitudinal front and rear strips along the longitudinal flanges of the shelf members having vertical spaced slots receiving the vertical edges of the vertical members therein.

9. A shelf assembly comprising a pair of upright channel members disposed with their channels in confronting relation and having vertical inturned retaining flanges, superposed shelf members between said channel members and having the ends thereof extending into the channels, an upstanding flange at the end of each shelf and a locking member at the end of each shelf extending transversely within the channels, said locking members being longer than the width of the shelf and engaging within the channels of the channel members and having their ends in interlocking engagement with the flanges of the channel members.

10. A shelf assembly comprising a pair of upright channel members, a pair of confronting vertical right angular flanges carried by each member, said channel members being disposed with their open sides toward each other, a back plate disposed in a vertical plane between and against the inner edges of said flanges and having an outwardly directed right angular flange at each vertical edge thereof engaging the inner sides of said pairs of flanges whereby said back plate will hold said members against lateral outward movement, a base disposed between the lower ends of said channel members, a lower shelf engaging on said base, a second shelf above the lower shelf, said shelves having end flanges, means including transverse strips longer than the width of the shelves extending between the vertical flanges of the channel members and end flanges of the shelves for cooperating between the shelves and flanges of the channel members for supporting the shelves one above the other, and means locking the ends of the shelves and the flanges of the channel members together.

11. A shelf assembly comprising a pair of upright channel members each having a pair of confronting vertical flanges and disposed with their channels toward each other, a back plate having outturned flanges at the vertical ends thereof directed outwardly at the flanges of the channel members and engaging the inner sides of said flanges whereby said back plate will hold said members against lateral outward movement,

a base disposed between the lower ends of said members, a lower shelf engaging on said base, a second shelf above said lower shelf, said shelves having upturned end flanges, means in the channels between said shelves for supporting said second shelf above said lower shelf and means including cooperating strips on the shelves and engaging within the flanges of the channels beyond the longitudinal edges of the shelves and with said upturned end flanges for locking said shelves and channel members together.

12. A shelf assembly comprising opposed spaced upright channel members disposed with the channels in confronting relation, vertical inturned retaining flanges on the opposite edges of said channel members, superposed shelf members between said channel members and having the ends thereof extending between said flanges into the channels, an upstanding flange at each end of said shelf members, and locking members longer than the width of said shelf members engaging between said retaining flanges and said upstanding flanges of the shelf members for locking said shelf members and channel members together.

13. A shelf assembly comprising opposed spaced upright channel members disposed with the channels in confronting relation, vertical opposed inturned retaining flanges on the opposite edges of said channel members, superposed shelf members between said channel members and having the ends thereof extending between said flanges into the channels, vertical members disposed between pairs of shelf members supporting an upper shelf member from a shelf therebeneath, lugs at the end portions of each shelf member, certain of said lugs extending upwardly, and locking members longer than the widths of said shelf members across the end portions of the shelf members and having their end portions extending between said retaining flanges and said upwardly extending lugs for locking said shelf members and channel members together against inward or outward separation.
